(57) **CLAIM**

The ornamental design for a tablet computer as shown and described.

DESCRIPTION

FIG. 1 is a front perspective view of the tablet computer according to our design.

FIG. 2 is a back perspective view thereof.

FIG. 3 is a front elevation view thereof.

FIG. 4 is a back elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged detail view of a portion of the tablet computer shown in area 9 in FIG. 1.

FIG. 10 is an enlarged detail view of a portion of the tablet computer shown in area 10 in FIG. 1.

FIG. 11 is an enlarged detail view of a portion of the tablet computer shown in area 11 in FIG. 1; and,

FIG. 12 is an enlarged detail view of a portion of the tablet computer shown in area 12 in FIG. 2.

The dashed broken lines in the drawings represent portions of the tablet computer that form no part of the claimed design. The dot-dash broken lines encircling portions of the tablet computer in FIGS. 1 and 2 and illustrated in enlarged views in FIGS. 9, 10, 11, and 12 form no part of the claimed design.

1 Claim, 12 Drawing Sheets
